UNITED STATES PATENT OFFICE.

OLUF TYBERG, OF BROOKLYN, NEW YORK.

TYPE-WRITING MACHINE.

SPECIFICATION forming part of Letters Patent No. 749,001, dated January 5, 1904.

Application filed March 9, 1899. Serial No. 708,423. (No model.)

To all whom it may concern:

Be it known that I, OLUF TYBERG, a citizen of the United States, residing in the borough of Brooklyn, city of New York, State of New York, have invented certain new and useful Improvements in Type-Writing Machines, of which the following is a specification.

In my application, filed May 8, 1897, Serial No. 635,681, I have shown and claimed a broadly novel organization wherein a wheel continuously revolving about a normally stationary axis has when desired imparted to it a diametrical bodily motion in a direction opposite to that in which is traveling the character thereon which has been selected to be printed from. The resultant of this composite motion is that the character on the wheel is momentarily maintained at the printing-point, and during that time an impression is taken therefrom. The machine herein described operates upon the same principle; and my present invention comprehends new and useful ways of controlling the operation of the continuously-revolving type-wheel, taking impressions therefrom, and effecting the required operations in a type-writing machine.

In the accompanying drawings, Figure 1 is a plan view; Fig. 2, a rear elevation on a somewhat larger scale with parts of the paper-roll and carriage broken away; Fig. 3, an end elevation looking at the right-hand end of Fig. 2; Fig. 4, a detail vertical sectional view on the line 4-4 of Fig. 2; Fig. 5, a vertical transverse section through the machine on the line 5-5 of Fig. 1; Fig. 6, a detail sectional view on the same line as Fig. 5, showing some parts of that figure in a different position; Fig. 7, a horizontal section on the line 7-7, Fig. 3; Fig. 8, a detailed horizontal section taken on an irregular line below the plane of section of Fig. 7 and showing merely the type-wheel shaft and some of the parts associated therewith. Fig. 9 is a longitudinal section through the paper-roll and certain parts associated therewith; Fig. 10, an end elevation looking at the right-hand end of the machine, showing the paper-roll, its carriage, and some associated parts; Fig. 11, an elevation of the face of the hand-wheel located at the left-hand end of the paper-roll; Fig. 12, a section through Fig. 11 on

the line 12-12; Fig. 13, a diagram view showing the movement of the type-wheel.

The frame of the machine may be of any appropriate form, and the construction shown need not be referred to except as it may seem desirable in connection with the description of operative parts of the mechanism.

I prefer to employ a rotary driver and have therefore shown a cammed, ribbed, or toothed driving-cylinder 1, appropriately mounted in bearings in the side plates of the machine, located somewhat above and in rear of the bank of keys. This cylindrical driver may be continuously rotated in any suitable manner. In the drawings I have shown a shaft 2 arranged parallel with the driver and having on one end a grooved pulley 3 and on the other end a beveled pinion 4. The grooved pulley may receive a band from any suitable motor—as, for instance, a treadle mechanism, a spring-motor or electric or other motor mounted upon the stand upon which the machine is placed, or a suitable motor, as an electric motor, may be located at the end of the shaft 2 and the armature thereof mounted thereon. The power means, however, for rotating the driver and the type-wheel form no part of this invention.

The beveled pinion 4, Fig. 3, meshes with a corresponding beveled gear 5 on the lower end of a short vertical shaft 6, which carries a spiral pinion 7, gearing with a spiral gear-wheel 8 upon the shaft or trunnion of the cylindrical driver 1. The shaft 6 carries also a toothed gear 9, that meshes with a toothed wheel 10 on the vertical type-wheel shaft 11, with which the type-wheel 12 revolves. When power is applied to the shaft 2, the driver 1 and the type-wheel are therefore continuously rotated at appropriate relative speeds. The type-wheel shaft has its upper bearing 13 on a flat bar or plate 14, capable of rocking upon an axis 15 out of line with the axis of the type-wheel shaft. The lower end of the type-wheel shaft has its bearings in a similar bar or plate 16, capable of turning upon an axis 17, coincident with the axis 15 of the upper plate 14.

The type-wheel may have several circumferential lines or series of characters. Two are shown, and the wheel should therefore be capable of assuming at the will of the op-

erator either of two positions. I have shown the type-wheel as carried by a sleeve 18, Figs. 3 and 4, of enlarged diameter, at its lower end, thus forming an annular shoulder 19, 5 that rests upon a collar 20, keyed to the type-wheel shaft. Below this shoulder the sleeve is slotted, and a lug 21 on the collar 20 occupies the slot. In the normal position with the shoulder 19 resting on the collar 20 the 10 upper series of characters on the face of the type-wheel is in the plane of printing. When the type-wheel and its sleeve are elevated as hereinafter described, the lower series of characters on the face of the wheel is brought 15 into the plane of printing. The shoulder 19 determines the normal lower position of the wheel, and a stop 221, shown as a roller mounted in bearings in an arm depending from the frame and against which the side 20 of the type-wheel may abut, determines the upper position of the wheel. The type-wheel rotates continuously in the direction of the arrow, Figs. 1 and 3. The driver rotates continuously in the direction of the arrow, 25 Figs. 3 and 5.

A vertical shaft 22, Figs. 3, 7, and 8, parallel with the type-wheel shaft, is mounted in suitable bearings, and arms 23 24, projecting radially therefrom, are operatively connected with the plates 14 and 16—as, for instance, in the manner shown in Fig. 8, where a pin on the plate 16 lies in a slot in the arm 24. The connection between the arm 23 and the upper plate 14 may be made in the same 30 manner. The type-wheel and associated parts are contained in a box or compartment located at the left-hand end of the frame.

The face of the type-wheel is divided into the required number of equal spaces. All of 40 the said spaces except one are occupied by the characters in the two series of characters shown on the wheel, the characters of one series being respectively exactly opposite the characters in the other series. The remaining space is left blank. Fast on the type-wheel shaft below the type-wheel is a ratchet-wheel 25, Figs. 3 and 7, of the same diameter as the type-wheel and having teeth equal in number to the spaces into which the face 45 of the type-wheel is divided. The point of each tooth of the wheel 25 is the same distance from the axis of the type-wheel shaft as is the face of the corresponding character on the type-wheel and in a line that divides 50 the face of said character centrally. These proportions or arrangements I prefer as giving the most perfect results. A lever 26, pivoted on the frame at 27 and normally held away from the ratchet-wheel 25 by its spring 55 28, is adapted to engage its teeth when actuated as hereinafter described. When the lever 26 is thrown into engagement with a tooth of the ratchet, the obstruction it opposes to the normal revolution of the wheel 60 about its center will cause the plates 14 16 to swing upon their center and carry the axis of the type-wheel through the arc indicated

by the solid arrow in Fig. 8, where the dotted arrow indicates the direction of rotation of the type-wheel. Referring to the diagram 70 view, Fig. 13, the axis on which the plates 14 16 swing is indicated by 15 17. The axis of the type-wheel in its normal position is indicated by *a*, and the same axis in another position to which it will be moved by the swinging plates 14 16 is indicated by *b*. The dotted line connecting the points marked *a* and *b* indicates the arc through which the type-wheel shaft may be swung. The type-wheel with its axis in the position indicated by *a* 75 is represented by the solid circle *c*, while the same wheel with its axis in position indicated by *b* is indicated by the circle *d*, while the same wheel with its axis in a position midway between the points *a* *b* is indicated by 80 the circle *e*. The shape or relation of the end of the lever 26 to the teeth of the wheel 25 is preferably such that when the wheel is arrested by the lever the point of the tooth which the lever engages is held at rest at a 85 point, as *y*, Fig. 13, in a line *x*, extending from the axis of the plates 14 16 and equally bisecting the arc described by the type-wheel shaft in moving from the position *a* to the position *b*, which point is the point of intersection 90 of the two circles representing the type-wheel and described, respectively, from the centers *a* *b*. It will therefore be apparent that the point of the ratchet-tooth engaged by the lever 26 will be held at rest so 95 far as its circumferential movement is concerned and that the corresponding character on the type-wheel will similarly be held at rest at the printing-point, while an impression may be taken therefrom without, 100 in fact, arresting the rotation of the type-wheel about its center. The action would be the same if the axis of the type-wheel were moved in a straight line represented by the cord of the arc *a* *b* or if the plates 105 14 16 were so pivoted as that the curve of the arc *a* *b* were reversed. If the movement were in a straight line and were equal and opposite to the movement of the type-wheel about its axis, the point upon the 110 type-wheel to be printed from would be stationary both as regards its circumferential movement and also as regards radial movement. If the curve of the arc of movement of the type-wheel shaft is as indicated in 115 Fig. 13, the point will have a slight radial movement away from the axis 15 17 along the line *x*, this movement being represented by the distance between the point *y* and the circle *e*, and if the pivots of the parts 14 16 120 were so located that the curve of the arc *a* *b* were reversed then there would be a slight radial movement toward the axis 15 17. To restate this matter in another way, it may be said that the movement bodily of the 125 type-wheel is opposite in direction to the direction of rotation of the rear or impression face of the type-wheel, and consequently a given point upon the rear face of the type- 130

wheel which by the rotation of the wheel about its axis would be carried past the printing-point at a uniform speed remains at that point for a moment, because the 5 bodily motion of the type-wheel gives to said point upon the rear face of the wheel a motion equal and opposite to that which said point receives by reason of the rotation of the wheel about its axis. By placing the 10 type-wheel on a vertical shaft I am enabled to place the ratchet-wheel 25 of the same diameter below it and below the carriage and obtain room for the lever 26.

The means I have shown of operating the 15 lever 26 to cause its engagement with the ratchet-wheel 25 are controlled by the finger-keys and are of course of such character that upon the depression of a given key the tooth in the ratchet that will be then engaged by 20 the end of the lever 26 is such as to cause the character on the wheel corresponding with the key depressed to remain at the printing-point.

The key-levers 29 are arranged horizontally 25 adjacent to the bottom plate of the frame and are appropriately fulcrumed upon knife-edges 30 and guided in slots or guideways formed in some of the frame-plates. The spacing-key 31 is elongated and located in 30 front of the bank of finger-keys, as usual, and is connected at each end by a lever 32 to a rock-shaft 33, mounted in bearings beneath the bottom plate of the machine and from which an arm 34 extends rearwardly to approximately the same distance as do the levers 29 of the other keys.

In that embodiment of my invention which the drawings illustrate the continuously-rotating driver 1 is provided with two spiral series of cams, ribs, or projections 35, a given projection 35 in one series being immediately opposite a corresponding projection in the other series, and there are in each series as many cams or projections as the number of 45 spaces into which the face of the type-wheel is divided. The type-wheel is geared to make two revolutions to one of the driver, and consequently each space on the type-wheel has two corresponding projections on the driver 50 appropriately located to effect the operation hereinafter described. Other relative speeds of rotation of the driver and type-wheel may be adopted and cams or projections on the driver appropriately arranged therefor. In 55 front of the driver on a fixed shaft 36 are mounted a series of independently-revolvable wheels 37, each in line with a pair of projections 35 on the driver and each having teeth 38, five such teeth being shown. The relation of each toothed wheel 37 to its operating cams or projections 35 on the driver is such that the wheel may occupy either the normal position, in which the projections on the driver do not come in contact with a tooth on 60 the wheel, or one in which the driver projections will in their revolution engage a tooth on the wheel and cause a partial revolution thereof.

Above the end of each finger-key 29 and normally in contact with it, but otherwise disconnected therefrom, is a vertically-movable 70 push-pin 39, preferably flat and adapted to slide vertically in a guide in the frame. Its enlarged lower end is slotted and seated upon a pin or rod 40, extending through the 75 slotted cross-piece 41 of the frame. A flat spring 42, mounted upon a cross-piece of the frame, presses upon the upper edge of the enlarged end of the vertically-sliding pin and holds it normally in its lowest position, thus 80 pressing down the inner end of the finger-key lever and maintaining the outer end of the lever in its normal elevated position. This spring also serves to return the vertical rod to its normal position after it has been rocked 85 rearwardly, as hereinafter described. On the opposite side of the enlarged end of each vertically-sliding pin is a projection 43, adapted to engage a cross-plate 44 and limit the upward movement of the rod when elevated by 90 the depression of the finger-key. Normally the upper end of the rod 39 is in contact with one of the teeth of its corresponding wheel 37. If now a finger-key be depressed to any extent, the corresponding vertically-sliding 95 pin 39 moves upwardly and partially turns its wheel 37. The wheel, however, is to be turned sufficiently far to bring a tooth thereon into the path of the projection 35 on the continuously-revolving driver 1. To insure 100 this, I provide for each wheel 37 a pivoted pawl or latch 45, normally pressed toward the wheel by a spring 46. At the end of this latch there is a slight projection having a short inclined face next the pivot of the 105 latch and a longer inclined face 47 forming the end of the latch. Normally a tooth 38 upon the wheel 37 is in engagement with the short inclined face, which serves to hold the wheel in the normal position. When the 110 wheel is moved by the pin 39, the tooth in engagement with the latch rides past the angle formed by the two inclined faces thereof and the longer inclined face 47 acts upon the tooth to bring and hold the wheel in proper position to have a tooth engaged by one of the 115 projections on the continuously-revolving driver. It will thus be apparent that the wheel is brought to the proper position each time that the key-lever is depressed, even 120 though but a partial depression of the key-lever occurs or the movement of the rod 39 is not made of sufficient extent to turn the wheel 37 the required distance. The projection 35 engages the tooth now lying in its path, Fig. 6, and moves the wheel 37 through 125 a partial revolution. When the projection 35 on the revolving driver has carried the tooth of the wheel 37 with which it is in engagement into such position that the projection 35 passes out of engagement with it, one 130 of the teeth of the wheel comes against the

short incline of the latch 45 and the wheel is again held at rest in its normal position. The arm 34 of the spacing-key 31 may operate upon a similar vertically-sliding rod, 5 which is elongated, as indicated by dotted lines 48 in Fig. 5, to extend through the bed-plate and into contact with the arm 34. The operation of spacing will be referred to later. During the partial rotation of the toothed 10 wheel by the driver the tooth thereof following that with which the push-pin 39 was in engagement before the movement commenced will strike against said pin and rock it rearwardly, this being permitted by the spring 42, which by its reaction returns it to the normal position immediately in rear of said tooth, Fig. 5, the wheel now being at rest again and held by the latch or pawl 45. Above the series of wheels 37 is a cross-bar 15 49, whose bottom is transversely slotted in line with each wheel and formed with a longitudinal channel or groove in its under face. A bolt or rod 50 occupies this channel, and in each slot is a lever 51, pivoted on the rod 20 50. One end of each lever 51 is normally thrown down so as to be engaged and lifted by a tooth on its corresponding toothed wheel 37 when that wheel is partially rotated by the driver, as already described. Its opposite 25 site end normally bears against a plate 52, which lies under the upper ends of all the levers 51 and is preferably inclined in the direction of its width from the rear downward toward the front of the machine. This 30 plate is carried by three arms 53, one connected with the plate near each end and one about its middle and all rocking upon a transverse shaft 54. The downwardly-projecting arm 55, carried by the central one of the 35 rocking arms 53, lies against the free end of the rocking lever 26, pivoted at 27, Fig. 7. Consequently when the plate 52 is pressed downwardly by reason of the free end of a lever 51 being lifted by one of the teeth of a 40 wheel 37, as indicated by the dotted lines in Fig. 5, the end of the lever 26 is thrown into engagement with the ratchet-wheel 25, fast on the type-wheel shaft, and the operation already described occurs. The spring 28 applied to the lever 26 serves to return it and the plate 52 and lever 51 to their normal positions. The relative positions of the teeth or projections upon the circumference of the driver and the characters in either series 45 upon the circumference of the type-wheel are such that when a given lever 51 is operated by its wheel in response to the depression of the corresponding finger-key, the corresponding character upon the type-wheel will for 50 an instant remain at the printing-point. I prefer that the cams or projections on the driver shall not be so related to the spaces into which the face of the type-wheel is divided as that the projection that causes the 55 arrest at the printing-point of a given space on the type-wheel shall be next on the driver to that which causes the arrest of an adja-

cent space on the type-wheel, but that they be separated by intervals of four or five or any other suitable number. Normally the 70 characters in the upper series of characters on the type-wheel are thus brought to and maintained at the printing position. The wheel may be raised on its shaft to bring the lower series into the printing-plane in a variety of ways. I have shown a shifting-key marked "Caps" in the drawings. It is connected by a link 56 with one end of a lever 57, pivoted on the frame, whose free end lies under and in contact with a short arm 58, 80 having one end pivoted in the frame and carrying at its free end a roller 59, running on the under side of a flange on the sleeve of the type-wheel, Figs. 3 and 7. When the "cap-lever" is depressed the type-wheel 85 is raised, its upward motion being limited by the roller-stop 221. Any of the character-keys may now be depressed while the cap or shifting key is held down and the operations already described will occur. When 90 the cap or shifting key is released, a spring 50, Fig. 2, connected to the type-wheel sleeve and ratchet-wheel 25, returns the parts to the normal position.

Any suitable hammer mechanism may be 95 employed. In the drawings I have shown upon the shaft 22, Figs. 1 and 8, a radial arm 61, to which is pivoted a latch 62, engaging a lug or projection on a short horizontal arm 63, pivoted to the frame. A spring 64 presses 100 the latch toward the projection on this arm and the outer end of the arm is connected by a rod 65 with one end of a lever 66, pivoted at the opposite end of the machine and extending rearwardly, its rear end being connected by a rod 67 with the hammer 68 adjacent to its pivot. Normally a spring 69 holds the hammer retracted and draws the arm 63 against a stop 70, Fig. 1. When a key is depressed and the operations described 105 occur to maintain the desired character upon the type-wheel for a moment at the printing-point, the initial rocking of the shaft 22 draws the latch 62 toward the left, as viewed in Fig. 1, and through the connections described the 110 hammer is thrown forward to take an impression from the type-wheel. This occurs during the early part of the movement or swing of the plates 14 16, and the feed of the carriage, as hereinafter described, may be 115 120 and in the organization shown is effected during the latter part of said movement. Some means is required for disconnecting the hammer from the swinging arm 61 after it has been thrown a sufficient distance to take a 125 proper impression from the type-wheel. This may be effected in the following manner: On the latch 62 is an inclined or cam projection 71, which works against a surface 72 on the frame, and when the latch has operated the 130 pivoted arm 63 through a sufficient distance to impart a proper impulse to the hammer the cam projection 71 will have moved the latch down to such extent as to disengage it

from the lug or tooth on the lever 63. On the recoil of the hammer and under the stress of its spring 69 the rod 67, lever 66, rod 65 push the lever 63 back into its normal position to be again engaged by the latch when the toothed wheel 25 has been released and the parts 14 16, in returning to their normal position under the stress of certain springs, referred to later, rock the shaft 22 and the 10 hammer-actuating arm 61 back into their normal position. The hammer is mounted upon an arm 73, secured to the frame at one side or end and extending along the rear of the frame and over the carriage toward the 15 other end of the machine, a space for the traverse of the paper being left between the arm and frame.

At the printing-point and between the hammer and the type-wheel is a shield 74, 20 consisting merely of a plate with an opening of proper area into which the hammer strikes in taking an impression. The purpose of this shield is to prevent the paper receiving any impression except from the character 25 against which it is directly forced by the hammer. In the series of characters on the type-wheel there is a blank space, which is held at the printing-point when the space-key is depressed and causes the actuation of 30 the mechanism, as already described. Consequently when the hammer is thrown forward upon the operation of the space-key there is a blank or depressed surface on the wheel opposite it and no impression is made 35 upon the paper. To prevent the blow of the hammer from bending the paper into this blank space or depression, I provide a stop 75 on the frame, Fig. 1, adjacent to the pivot of the hammer by which its movement toward 40 the type-wheel is limited.

An inking-roll 76 has its bearings in bifurcations of an arm or bracket 77, Fig. 1, hinged in a recess in the frame. The butt of the bracket is squared (like that of a knife-blade) and a plate-spring 78 bears against it. The spring holds the bracket in normal position, and yet it may be swung out and so held by the spring, as shown by dotted lines. A thumb-screw 79 affords a suitable means 50 of adjusting the inking-roll with reference to the face of the type-wheel.

The carriage 80 travels in suitable guides or ways of ordinary construction at the rear of the machine and has a standard 81 at each 55 end in which the large paper-feed roll 82 has its bearings. A smaller feed-roll 83, co-operating with the larger one, is mounted in front of it and also has its bearings in the end pieces 81 of the carriage. The bearings of 60 the latter roll may, as is common to paper-feed devices of this character, be mounted in bearing-blocks held in position by springs and capable of yielding. A curved guide plate or table 84 directs the paper to the bite 65 of the rolls 82 and 83, whence it passes upwardly between the face of the type-wheel and the shield 74 and when it rises it will

fall backwardly and lie upon the inclined table 85, which affords a convenient support in making erasures and corrections. The 70 forward step-by-step movement of the carriage will first be described and then the operation of the line-spacing mechanism.

When the shaft 22, Figs. 7 and 8, is rocked by the swinging of the plates 14 16 in which 75 the type-wheel shaft is mounted, an arm 86 thereon moves a lever 87 against the tension of its spring 88, seated in a socket in the frame and compressed by a plunger on the lever. The opposite end of the lever projects toward 80 the rear of the machine in front of a vertical arm 89, pivoted at its lower end and urged by its spring 90 against the end of the lever 87, which works in a slot (shown by dotted lines in Fig. 2) in the rear vertical frame-plate of 85 the machine. The rack 91, carried by the carriage 80, is in rear of the arm 89. A feed-pawl 92, pivoted on the arm 89, is normally urged upwardly by its spring 93 and has a lateral rearwardly-projecting tooth 94, adapted to engage the teeth of the rack. It also has on its upper edge (shown in dotted lines, Fig. 2) a projection 95, the upper edge of which inclines downwardly toward the pivot of the latch and normally bears against a pin 96, projecting 90 from the rear frame-plate 97, thereby holding the tooth 94 out of engagement with the rack. When a key-lever is depressed and the ratchet-wheel 25 on the type-wheel shaft is engaged by the end of the lever 26, causing the plates 100 in which the type-wheel shaft is mounted to swing upon their pivots, and thus maintain the required character for a moment at the printing-point, the first portion or period of movement of the plates 14 16 and the shaft 105 22 results in thus holding the character at the printing-point and in the actuation of the hammer to take an impression therefrom. During this period of the movement while the hammer is operated and released as described 110 the pin 96 rides down the incline of the projection 95 on the pawl 92 and allows it to rise and its tooth 94 to enter a notch in the rack. The final movement of the parts referred to causes the end of the lever 87 to 115 continue its movement, and thereby cause the advancement of the carriage one step after the hammer has dropped back. Afterward all the parts are returned to their normal positions by the reaction of the spring 90 applied 120 to the arm 89 and spring 88 applied to lever 87.

The detent-pawl 98 is pivoted upon a post 99, projecting laterally from the rear vertical frame-plate 97, and a spring 100, coiled around 125 its bearing, normally throws upwardly one end of the pawl and causes a lateral tooth 101 thereon to normally engage the rack. The opposite end of the pawl has on its lower edge a projection 102, the inner edge of which is 130 inclined, and between such inclined edge and the pivot of the pawl there normally lies a projection 103 on a pivoted lever 104, the upper end of which lever extends above the detent-

pawl 98 into the path of a pin 105, projecting from one of the parallel webs 106 on the bottom of the carriage. The lever 104 is a bell-crank lever, and its horizontal arm 107 is connected by a link 108 with an arm 109, Fig. 5, connected with a rock-shaft 110, from which extend radial arms 111, carrying a locking-bar 112, adapted to be thrown forward over the ends of the key-levers 29 to lock them. A spring 113, applied beneath the arm 109, tends normally to urge it upward, and consequently to throw the locking-plate over the ends of the key-levers and to raise the horizontal arm 107 of the lever 104. The parts are, however, normally held in the position shown in Figs. 2 and 5 by a three-armed latch 114, having a spring coiled around its bearing and tending to throw its hooked arm 115 upwardly to engage the projection 103 on the lever 104. The second arm 116 of this three-armed latch extends upwardly between the parallel ribs 106 on the bottom of the carriage in a position to be struck by a pin 118, carried by one of these ribs. The third arm 117 of this latch normally lies against the upper end of a vertical rod 119, the lower end of which bears upon a lever 120, pivoted at 121 and connected at its front end with a vertically-moving rod 122, having a finger-piece 123 upon its upper end located at the left inner corner of the keyboard, as seen at Fig. 7. The operation of these parts is as follows: As the carriage feeds from right to left in the ordinary way and the limit of its forward movement is approached, the pin 118 strikes the arm 116 of the three-armed latch and throws the arm 115 thereof out of engagement with the projection 103 on the lever 104. The spring 113, acting against the under side of the arm 109, projecting from the rock-shaft 110, Fig. 5, now urges upward the horizontal arm 107 of the lever 104 and throws the other end of the lever to the right, as viewed in Fig. 2. The projection 103 on the lever 104 rides against the projection 102 on the detent-pawl and throws its tooth 101 out of engagement with the rack. The actuating or feeding pawl 92 being normally out of engagement with the rack the effect of the movement of the parts just described is to cause the retreat or return movement of the carriage under the stress of the cord 124 of the spring-drum 125. The carriage is thus returned to the initial position for the commencement of a new line of printing. As the carriage approaches this initial position the pin 105 thereon strikes the end of the lever 104 and causes the projection 103 thereon to ride over the catch or hook of the latch 115 and bring the parts to the normal position. (Indicated in Fig. 2.) Whenever it is desired to return the carriage to the initial position before the pin 118 engages the arm 116 of the three-armed latch, as described, the operator may press upon the key 123, thus forcing the rod 119 against the arm 117 of the three-armed latch and throwing its arm 115

out of engagement with the projection on the lever 104. During the return movement of the carriage the locking-bar 112 lies above the ends of all the key-levers and prevents the depression of any character-key.

The line-spacing mechanism shown in the drawings, Figs. 9 to 12, is constructed and operated as follows: The larger paper-roll 82 may be hollow, as shown, Fig. 9, or may merely be bored out axially for the reception of the shaft 126, which is loosely fitted therein, so that the roll and shaft may turn relatively to each other. The roll has trunnions 127 128, turning in bearings in the vertical end plates 80 or standards 81 of the carriage. At the left-hand end of the roll the trunnion 127 extends beyond its bearing and has attached to it a disk 129, preferably flanged for convenience in using it as a hand-wheel, and outside of the disk a star-toothed wheel 130. A radial arm 131, keyed to the end of the shaft, carries a pivoted latch 132, having a spring 133, working against a wedge-shaped projection on the hub of the latch and serving to hold it either in or out of engagement with the teeth of the wheel 130. The latch has a thumb-piece 134, by which it may conveniently be thrown into either position. At the opposite end of the roll the trunnion 128 beyond its bearing is provided with a coiled spring 135, one end of which is attached to the trunnion and the other engaged with a radial arm 136, keyed to the shaft 126 and carrying at its end a roller 137 so arranged and adapted as to strike against the inclined or curved cam edge 138 of a plate 139, lying parallel with the axis of the roll. This cam-plate is carried by a disk 140, having a hollow boss or hub 141, turning in a bearing in a part 142 of the frame. The disk has three apertures 143 therein, adapted to be entered by a spring locking-pin 144, and may therefore be set in either of three positions at will. The end of the shaft 126 preferably extends beyond the radial arm 136, and its end is chamfered, so that it will readily enter the bore of the hub 141, through which it extends when the carriage is in the normal or initial position, as shown in Fig. 9. When the carriage after having completed its forward excursion is returned to its initial position by the strain of the spring drum-cord 124, the roller 137 strikes and rides along the inclined face of the cam 138 and produces a partial revolution of the shaft, contracting the coiled spring 135 and through it and the latch 132 turning the feed-roll 82 through the required distance to give the desired line-space on the paper, which is determined by the position of the cam 138. As the carriage is now fed forward step by step in the printing of a new line the roll 137 slowly runs down the cam edge 138, gradually relaxing the spring 135 without causing any movement of the roll 82, and comes against a stop 145, Figs. 1, 2, and 10. The latch 132 may be thrown out of en-

gagement with the star-toothed wheel and be so held by its spring and the roll 82 turned by hand.

The bearing of the lower plate 16, in which the type-wheel shaft is mounted, is constructed as follows: A plate 146, having an annular track containing antifriction-balls, is seated in the frame and has a central aperture or bearing, which also extends through the frame, in which is seated the bearing or journal 17 of the plate, which rests upon the bearing-balls. A washer 147 may be applied to the end of the journal and held in place by a screw. The bearing of the upper plate 14 is constructed as follows: A flanged bushing 148 is fitted to move vertically in a correspondingly-shaped open socket in the frame. Its vertical movement is limited by its flange, and it is held against rotation by a key 149, working in a keyway in its socket. The bushing is bored throughout its length, and the upper part of the bore is of larger diameter than the lower part, thus forming a shoulder 150. Its under face is provided with an annular channel concentric to the bore of the bushing, in which are antifriction-balls. The journal 15 of the plate 14 is inserted from below. The plate bears against the antifriction-balls and is held in the bushing by a washer 151, bearing against the shoulder 150 and secured on the end of the journal by a screw. A screw-bolt 152 works in the upper part of the enlarged bore of the bushing and is formed with an enlarged head having an annular groove 153 therein, in which lie the two horns or bifurcations 154 of the top plate 155, which is secured in position by screws, as seen in Fig. 1. The screw-bolt 152 may therefore be rotated to raise or lower the bushing, which is held against turning by the key 149, and adjust the bearing of the type-wheel shaft.

A machine of the general type disclosed herein and in my prior application before mentioned is believed to be a radical departure from the machines of the prior art. While it is intended that the generic claims thereto shall be made in said prior application, it is apparent that the invention herein set forth is of a broad character, subordinate only to the generic claims of the other application and that the movements, operation, or behavior of many parts of the organization illustrated may be effected by mere change in the mechanical form in which the principle of my invention may be embodied. It is not, therefore, my intention, nor do I desire to limit my claims, to the special construction herein set forth.

I claim as my invention—

60 1. The combination of a continuously-revolving type-wheel having characters in fixed relation thereto, mechanism whereby any character thereon may be momentarily maintained at the printing-point, a driver, and a series of devices normally inactive but each at will operated by the driver to actuate said mechanism.

2. The combination of a continuously-revolving type-wheel having characters in fixed relation thereto, mechanism whereby any character thereon may be momentarily maintained at the printing-point, a driver, a series of devices normally inactive but each at will operated by the driver to actuate said mechanism and a coöperating hammer mechanism for taking impressions from the type-wheel. 75

3. The combination of a continuously-revolving type-wheel having characters in fixed relation thereto, mechanism whereby any character thereon may be momentarily maintained at the printing-point, a driver, a series of devices normally inactive but each at will operated by the driver to actuate said mechanism, a carriage and mechanism for feeding it forward. 80

4. The combination of a continuously-revolving type-wheel having characters in fixed relation thereto, mechanism whereby any character thereon may be momentarily maintained at the printing-point, a driver, a series of devices normally inactive but each at will operated by the driver to actuate said mechanism, a coöperating hammer mechanism for taking impressions from the type-wheel, a carriage and mechanism for feeding it forward. 95

5. The combination of a continuously-revolving type-wheel having characters in fixed relation thereto, mechanism whereby any character thereon may be momentarily maintained at the printing-point, a continuously-rotating driver, and a series of devices normally inactive but each at will operated by the continuously-rotating driver to actuate said mechanism. 100

6. The combination of a continuously-revolving type-wheel having characters in fixed relation thereto, mechanism whereby any character thereon may be momentarily maintained at the printing-point, a continuously-rotating driver, a series of devices normally inactive but each at will operated by the continuously-rotating driver to actuate said mechanism, and a coöperating hammer mechanism for taking impressions from the type-wheel. 110

7. The combination of a continuously-revolving type-wheel having characters in fixed relation thereto, mechanism whereby any character thereon may be momentarily maintained at the printing-point, a continuously-rotating driver, a series of devices normally inactive but each at will operated by the continuously-rotating driver to actuate said mechanism, a carriage and mechanism for feeding it forward. 120

8. The combination of a continuously-revolving type-wheel having characters in fixed relation thereto, mechanism whereby any character thereon may be momentarily maintained at the printing-point, a continuously-rotating driver, a series of devices normally inactive but each at will operated by the continuously-rotating driver to actuate said mech-

anism, a coöperating hammer mechanism for taking impressions from the type-wheel, a carriage, and mechanism for feeding it forward.

9. The combination of a continuously-revolving type-wheel so mounted as to be moved bodily, mechanism whereby the type-wheel may be so moved to thereby maintain any character thereon momentarily at the printing-point, a driver and a series of devices each adapted at will to be operated by the driver to actuate said mechanism.

10. The combination of a continuously-revolving type-wheel so mounted as to be moved bodily, mechanism whereby the type-wheel may be so moved to thereby maintain any character thereon momentarily at the printing-point, a driver, a series of devices each adapted at will to be operated by the driver to actuate said mechanism, and a coöperating hammer mechanism for taking impressions from the type-wheel.

11. The combination of a continuously-revolving type-wheel so mounted as to be moved bodily, mechanism whereby the type-wheel may be so moved to thereby maintain any character thereon momentarily at the printing-point, a driver, a series of devices each adapted at will to be operated by the driver to actuate said mechanism, a carriage, and mechanism for feeding it forward.

12. The combination of a continuously-revolving type-wheel so mounted as to be moved bodily, mechanism whereby the type-wheel may be so moved to thereby maintain any character thereon momentarily at the printing-point, a driver, a series of devices each adapted at will to be operated by the driver to actuate said mechanism, a coöperating hammer mechanism for taking impressions from the type-wheel, a carriage, and mechanism for feeding it forward.

13. The combination of a continuously-revolving type-wheel so mounted as to be moved bodily, mechanism whereby the type-wheel may be so moved to thereby maintain any character thereon momentarily at the printing-point, a continuously-rotating driver, and a series of devices each adapted at will to be operated by the continuously-rotating driver to actuate said mechanism.

14. The combination of a continuously-revolving type-wheel so mounted as to be moved bodily, mechanism whereby the type-wheel may be so moved to thereby maintain any character thereon momentarily at the printing-point, a driver, a series of devices interposed between the driver and said mechanism, a series of finger-keys corresponding with characters on the type-wheel, and means whereby when a finger-key is depressed the corresponding one of said devices is actuated by the driver to operate said mechanism to maintain the corresponding character upon the type-wheel momentarily at the printing-point.

15. The combination of a continuously-re-

volving type-wheel so mounted as to be moved bodily, mechanism whereby the type-wheel may be so moved to thereby maintain any character thereon momentarily at the printing-point, a driver, a series of devices interposed between the driver and said mechanism, a series of finger-keys corresponding with characters on the type-wheel, means whereby when a finger-key is depressed the corresponding one of said devices is actuated by the driver to operate said mechanism to maintain the corresponding character upon the type-wheel momentarily at the printing-point, and a coöperating hammer mechanism for taking impressions from the type-wheel.

16. The combination of a continuously-revolving type-wheel so mounted as to be moved bodily, mechanism whereby the type-wheel may be so moved to thereby maintain any character thereon momentarily at the printing-point, a driver, a series of devices interposed between the driver and said mechanism, a series of finger-keys corresponding with characters on the type-wheel, means whereby when a finger-key is depressed the corresponding one of said devices is actuated by the driver to operate said mechanism to maintain the corresponding character upon the type-wheel momentarily at the printing-point, a carriage, and mechanism for feeding it forward.

17. The combination of a continuously-revolving type-wheel so mounted as to be moved bodily, mechanism whereby the type-wheel may be so moved to thereby maintain any character thereon momentarily at the printing-point, a driver, a series of devices interposed between the driver and said mechanism, a series of finger-keys corresponding with characters on the type-wheel, means whereby when a finger-key is depressed the corresponding one of said devices is actuated by the driver to operate said mechanism to maintain the corresponding character upon the type-wheel momentarily at the printing-point, a coöperating hammer mechanism for taking impressions from the type-wheel, a carriage, and mechanism for feeding it forward.

18. The combination of a continuously-revolving type-wheel so mounted as to be moved bodily, mechanism whereby the type-wheel may be so moved to thereby maintain any character thereon momentarily at the printing-point, a continuously-rotating driver, a series of devices interposed between the continuously-rotating driver and said mechanism, a series of finger-keys corresponding with characters on the type-wheel, and means whereby when a finger-key is depressed the corresponding one of said devices is actuated by the continuously-rotating driver to operate said mechanism to maintain the corresponding character upon the type-wheel momentarily at the printing-point.

19. The combination of a continuously-revolving type-wheel, mechanism whereby any

character thereon may be momentarily maintained at the printing-point, a driver, a series of devices interposed between the driver and said mechanism, a series of finger-keys corresponding with characters on the type-wheel, and means whereby when a finger-key is depressed the corresponding one of said devices is actuated by the driver to operate said mechanism to maintain the corresponding character upon the type-wheel momentarily at the printing-point.

20. The combination of a continuously-revolving type-wheel, mechanism whereby any character thereon may be momentarily maintained at the printing-point, a driver, a series of devices interposed between the driver and said mechanism, a series of finger-keys corresponding with characters on the type-wheel, means whereby when a finger-key is depressed the corresponding one of said devices is actuated by the driver to operate said mechanism to maintain the corresponding character upon the type-wheel momentarily at the printing-point, and a coöperating hammer mechanism for taking impressions from the type-wheel.

21. The combination of a continuously-revolving type-wheel, mechanism whereby any character thereon may be momentarily maintained at the printing-point, a driver, a series of devices interposed between the driver and said mechanism, a series of finger-keys corresponding with characters on the type-wheel, means whereby when a finger-key is depressed the corresponding one of said devices is actuated by the driver to operate said mechanism to maintain the corresponding character upon the type-wheel, momentarily at the printing-point, a carriage and mechanism for feeding it forward.

22. The combination of a continuously-revolving type-wheel, mechanism whereby any character thereon may be momentarily maintained at the printing-point, a driver, a series of devices interposed between the driver and said mechanism, a series of finger-keys corresponding with characters on the type-wheel, means whereby when a finger-key is depressed the corresponding one of said devices is actuated by the driver to operate said mechanism to maintain the corresponding character upon the type-wheel momentarily at the printing-point, a coöperating hammer mechanism for taking impressions from the type-wheel, a carriage, and mechanism for feeding it forward.

23. The combination of a continuously-revolving type-wheel, mechanism whereby any character thereon may be momentarily maintained at the printing-point, a continuously-rotating driver, a series of devices interposed between the continuously-rotating driver and said mechanism, a series of finger-keys corresponding with characters on the type-wheel, and means whereby when a finger-key is depressed the corresponding one of said devices is actuated by the continuously-rotating driver to operate said mechanism to maintain

the corresponding character upon the type-wheel momentarily at the printing-point.

24. The combination of a continuously-revolving type-wheel so mounted as to be moved bodily in a direction opposed to the direction of rotation of its impression side, a toothed wheel revolving and movable therewith, and a device for at will engaging the toothed wheel and thereby causing the bodily movement of the type-wheel to momentarily maintain any character thereon at the printing-point.

25. The combination of a continuously-revolving type-wheel so mounted as to be moved bodily in a direction opposed to the direction of rotation of its impression side, a toothed wheel revolving and movable therewith, a device for at will engaging the toothed wheel and thereby causing the bodily movement of the type-wheel to momentarily maintain any character thereon at the printing-point, and a coöperating hammer mechanism for taking impressions from the type-wheel.

26. The combination of a continuously-revolving type-wheel so mounted as to be moved bodily in a direction opposed to the direction of rotation of its impression side, a toothed wheel revolving and movable therewith, a device for at will engaging the toothed wheel and thereby causing the bodily movement of the type-wheel to momentarily maintain any character thereon at the printing-point, a carriage, and mechanism for feeding it forward.

27. The combination of a continuously-revolving type-wheel so mounted as to be moved bodily in a direction opposed to the direction of rotation of its impression side, a toothed wheel revolving and movable therewith, a device for at will engaging the toothed wheel and thereby causing the bodily movement of the type-wheel to momentarily maintain any character thereon at the printing-point, a coöperating hammer mechanism for taking impressions from the type-wheel, a carriage, and mechanism for feeding it forward.

28. The combination of a continuously-revolving type-wheel so mounted as to be movable bodily in a direction opposed to the direction of rotation of its impression side, a toothed wheel revolving and movable therewith, a device for engaging the toothed wheel and thereby causing the bodily movement of the type-wheel to maintain a character thereon momentarily at the printing-point, mechanism for operating said device, finger-keys corresponding with characters on the type-wheel, and means whereby when a finger-key is depressed said mechanism is operated to maintain the corresponding character on the type-wheel momentarily at the printing-point.

29. The combination of a continuously-revolving type-wheel so mounted as to be movable bodily in a direction opposed to the direction of rotation of its impression side, a toothed wheel revolving and movable there-

with, a device for engaging the toothed wheel and thereby causing the bodily movement of the type-wheel to maintain a character thereon momentarily at the printing-point, mechanism for operating said device, finger-keys corresponding with characters on the type-wheel, means whereby when a finger-key is depressed said mechanism is operated to maintain the corresponding character on the type-wheel momentarily at the printing-point, and a coöperating hammer mechanism for taking impressions from the type-wheel.

30. The combination of a continuously-revolving type-wheel so mounted as to be movable bodily in a direction opposed to the direction of rotation of its impression side, a toothed wheel revolving and movable therewith, a device for engaging the toothed wheel and thereby causing the bodily movement of the type-wheel to maintain a character thereon momentarily at the printing-point, mechanism for operating said device, finger-keys corresponding with characters on the type-wheel, means whereby when a finger-key is depressed said mechanism is operated to maintain the corresponding character on the type-wheel momentarily at the printing-point, a carriage and mechanism for feeding it forward.

31. The combination of a continuously-revolving type-wheel so mounted as to be movable bodily in a direction opposed to the direction of rotation of its impression side, a toothed wheel revolving and movable therewith, a device for engaging the toothed wheel and thereby causing the bodily movement of the type-wheel to maintain a character thereon momentarily at the printing-point, mechanism for operating said device, finger-keys corresponding with characters on the type-wheel, means whereby when a finger-key is depressed said mechanism is operated to maintain the corresponding character on the type-wheel momentarily at the printing-point, a coöperating hammer mechanism for taking impressions from the type-wheel, a carriage, and mechanism for feeding it forward.

32. The combination of a continuously-revolving type-wheel so mounted as to be movable bodily in a direction opposed to the direction of rotation of its impression side, a toothed wheel revolving and movable with the type-wheel, a lever or movable stop for engaging the toothed wheel and thereby causing the bodily movement of the type-wheel, mechanism for actuating said lever, a driver, and a series of devices interposed between the driver and said mechanism normally inactive but operated at will by the driver to actuate said mechanism.

33. The combination of a continuously-revolving type-wheel so mounted as to be movable bodily in a direction opposed to the direction of rotation of its impression side, a toothed wheel revolving and movable with the type-wheel, a lever or movable stop for engaging the toothed wheel and thereby caus-

ing the bodily movement of the type-wheel, mechanism for actuating said lever, a driver, a series of devices interposed between the driver and said mechanism normally inactive but operated at will by the driver to actuate said mechanism, a coöperating hammer mechanism for taking impressions from the type-wheel.

34. The combination of a continuously-revolving type-wheel so mounted as to be moved bodily in a direction opposed to the direction of rotation of its impression side, a toothed wheel revolving and movable with the type-wheel, a lever or movable stop for engaging the toothed wheel and thereby causing the bodily movement of the type-wheel, mechanism for actuating said lever, a driver, a series of devices interposed between the driver and said mechanism normally inactive but operated at will by the driver to actuate said mechanism, a carriage, and mechanism for feeding it forward.

35. The combination of a continuously-revolving type-wheel so mounted as to be moved bodily in a direction opposed to the direction of rotation of its impression side, a toothed wheel revolving and movable with the type-wheel, a lever or movable stop for engaging the toothed wheel and thereby causing the bodily movement of the type-wheel, mechanism for actuating said lever, a driver, a series of devices interposed between the driver and said mechanism normally inactive but operated at will by the driver to actuate said mechanism, a coöperating hammer mechanism for taking impressions from the type-wheel, a carriage, and mechanism for feeding it forward.

36. The combination of a continuously-revolving type-wheel so mounted as to be moved bodily in a direction opposed to the direction of rotation of its impression side, a toothed wheel revolving and movable with the type-wheel, a lever or movable stop for engaging the toothed wheel and thereby causing the bodily movement of the type-wheel, mechanism for actuating said lever, a driver, a series of devices interposed between the driver and said mechanism, a series of finger-keys corresponding with characters on the type-wheel, and means whereby when a finger-key is depressed the corresponding one of said devices is operated by the driver to maintain the corresponding type-wheel character momentarily at the printing-point.

37. The combination of a continuously-revolving type-wheel having multiple series of characters thereon and so mounted as to be capable of axial movement and movement bodily at right angles to its axis, means for at will moving it axially to bring the desired series of characters into the printing-plane, and means for moving it bodily to momentarily maintain the desired character thereon at the printing-point.

38. The combination of a continuously-rotated cammed or toothed driver, a continu-

ously-rotated type-wheel, a series of finger-keys corresponding with characters on the type-wheel, a series of devices, one for each finger-key interposed between the finger-keys and driver and normally out of operative engagement with the driver but respectively actuated thereby when the corresponding finger-keys are depressed, and normally inactive mechanism for maintaining any character upon the type-wheel at rest for a moment at the printing-point, operated by one of said interposed devices to momentarily maintain a character on the type-wheel at the printing-point when the corresponding finger-key is depressed.

39. The combination of a continuously-rotated cammed or toothed driver, a continuously-rotated type-wheel, a series of finger-keys corresponding with characters on the type-wheel, a series of devices, one for each finger-key interposed between the finger-keys and driver and normally out of operative engagement with the driver but respectively actuated thereby when the corresponding finger-keys are depressed, normally inactive mechanism for momentarily maintaining any character upon the type-wheel at the printing-point, operated by one of said interposed devices when the corresponding finger-key is depressed, and coöperating hammer mechanism for then taking an impression from the type-wheel.

40. The combination of a continuously-rotated cammed or toothed driver, a continuously-rotated type-wheel, a series of finger-keys corresponding with characters on the type-wheel, a series of devices, one for each finger-key interposed between the finger-keys and driver and normally out of operative engagement with the driver but respectively actuated thereby when the corresponding finger-keys are depressed, and normally inactive mechanism operated by one of said interposed devices when the corresponding key is depressed for imparting to the wheel a movement bodily in a direction opposed to the rotary motion of the impression side of the type-wheel whereby any character thereon may be momentarily maintained at the printing-point when the corresponding finger-key is depressed.

41. The combination of a continuously-rotated cammed or toothed driver, a continuously-rotated type-wheel, a series of finger-keys corresponding with characters on the type-wheel, a series of toothed wheels one for each finger-key capable of independent rotation and normally out of operative engagement with the driver but respectively operated thereby on the depression of the corresponding finger-keys, and mechanism for momentarily maintaining any character upon the type-wheel at the printing-point operated by the respective toothed wheels when the corresponding finger-keys are depressed.

42. The combination of a continuously-rotated cammed or toothed driver, a continuously-rotated type-wheel, a series of finger-keys corresponding with characters on the type-wheel, a series of toothed wheels one for each finger-key capable of independent rotation and normally out of operative engagement with the driver but respectively operated thereby on the depression of the corresponding finger-keys, and mechanism for imparting to the wheel a movement bodily in a direction opposed to the rotary motion of the impression side of the type-wheel whereby any character thereon may be maintained at rest at the printing-point, operated by the respective toothed wheels to maintain given characters on the wheel at the printing-point when the corresponding finger-keys are depressed.

43. The combination of a cylindrical driver having cams or projections disposed about its circumference in different circumferential and diametrical lines, a type-wheel having characters thereon disposed in diametrical lines correspondingly with the disposition of the cams or projections on the driver, means for continuously rotating the driver and type-wheel, a series of finger-keys corresponding with characters on the type-wheel, a series of devices, one for each finger-key, each adapted on the depression of its key to be actuated by the driver, and mechanism operated by said devices when so actuated by the driver for moving the type-wheel bodily in a direction opposed to the rotary motion of its impression side.

44. The combination of a carriage adapted to be fed step by step, a cylindrical driver having cams or projections disposed about its circumference in different circumferential and diametrical lines, a type-wheel having characters thereon disposed in diametrical lines correspondingly with the disposition of the cams or projections on the driver, means for continuously rotating the driver and type-wheel, a series of finger-keys corresponding with characters on the type-wheel, a series of devices one for each finger-key, each adapted on the depression of its key to be actuated by the driver, mechanism operated by said devices for moving the type-wheel bodily in a direction opposed to the rotary motion of its impression side, and means for then first taking an impression from the type-wheel and afterward feeding forward the carriage.

45. The combination of a rotating cammed or toothed driver, a toothed wheel normally out of engagement with the driver, and means for at will bringing the toothed wheel into engagement with the driver to be partially rotated thereby.

46. The combination of a rotating cammed or toothed driver, a toothed wheel normally out of engagement with the driver, a lever or device for giving an initial impulse of partial rotation to the wheel, means for then automatically completing such partial revolution.

tion of the wheel to bring a tooth thereon into engagement with the driver to be partially rotated thereby.

47. The combination of a revolving cammed or toothed driver, a series of toothed wheels capable of independent rotation, mounted adjacent to the driver and normally out of engagement therewith, and means for at will partially rotating each wheel to bring a tooth thereon into operative engagement with the driver which then turns the wheel through a partial revolution.

48. The combination of a revolving cammed or toothed driver, a series of toothed wheels capable of independent rotation, mounted adjacent to the driver and normally out of operative engagement with the driver, a latch for each wheel holding the wheel in its normal position and having an inclined face adapted to act upon said tooth of the wheel, means for at will partially rotating each wheel to move the tooth engaged by the latch to such position that the inclined face of the latch acts thereon to complete the movement of the wheel to a position in which a tooth thereon will be engaged by the driver which positively rotates it through a partial revolution to its normal or initial position.

49. The combination of a revolving cammed or toothed driver, a series of finger-keys, a series of toothed wheels capable of independent rotation, one for each finger-key, mounted adjacent to the driver and normally out of operative engagement therewith, means for at will partially rotating each wheel to bring a tooth thereon into position to be engaged by a projection on the driver, which means consist of a device operated on the depression of the corresponding finger-key to impart to the wheel an initial motion about its axis and a device for automatically completing the partial rotation of the wheel to bring a tooth thereof into the path of the driver.

50. The combination of a rotating cammed or toothed driver, a series of toothed wheels mounted adjacent to the driver and normally out of engagement therewith, a latch or pawl for each wheel having a shoulder or projection normally engaging a tooth of the wheel to hold it in its normal position and an inclined face that acts upon said tooth, when it has been moved past the shoulder of the latch by a partial revolution of the wheel, to further move the wheel into such position that a tooth thereon will be engaged by the driver, a series of finger-keys, one for each wheel, and a device operated by each key to commence the partial rotation of its wheel 60 which is completed by the inclined face of the latch.

51. The combination of a revolving cammed or toothed driver, the finger keys or levers, a series of toothed wheels adapted upon the depression of their corresponding levers to be partially rotated by the driver, a series of pivoted levers operated by the teeth of the

wheels when so partially rotated, a continuously-revolving type-wheel mounted so as to be movable bodily in the direction and for the purpose set forth, and mechanism for effecting such movement operated by said levers.

52. The combination of a revolving cammed or toothed driver, a series of toothed wheels mounted adjacent to the driver, capable of independent rotation and normally out of operative engagement therewith, means whereby the driver may be caused at will to partially revolve either of such wheels, a continuously-revolving type-wheel, a shaft mounted in movable supports, mechanism for moving said supports to impart a movement bodily to the type-wheel in the direction and for the purpose set forth, and operative connections between such mechanism and the respective toothed wheels.

53. The combination of a rotated cammed or toothed driver, a series of toothed wheels capable of independent rotation, arranged adjacent to the driver and normally out of operative engagement therewith, means for at will partially rotating each wheel to bring a tooth thereon into the path of the driver whereby the wheel is partially rotated through a partial revolution to its initial or normal position, a continuously-revolving type-wheel, mechanism for moving the wheel bodily for the purpose described, and operative connections interposed between such mechanism and the respective toothed wheels and operated by the wheels when partially rotated by the driver.

54. The combination of a revolving driver having projections thereon, a series of toothed wheels capable of independent rotation, mounted adjacent to the driver and normally out of operative engagement therewith, a series of finger-keys, devices by which on the depression of a finger-key an initial rotary movement is imparted to the corresponding wheel, means for then completing a given partial rotation of the wheel to bring a tooth thereon into the path of the driver by which the wheel is positively rotated into its normal or initial position, a continuously-revolving type-wheel, mechanism for moving it bodily for the purpose described, and operative connections between such mechanism and the respective toothed wheels.

55. The combination of a continuously-revolving cammed or toothed driver, a series of toothed wheels mounted adjacent thereto and normally out of operative engagement therewith, a series of finger keys or levers, means whereby upon the depression of a lever the corresponding toothed wheel is partially rotated to bring a tooth thereon into the path of the driver whereby it is driven through a partial revolution to its normal or initial position, a continuously-revolving type-wheel revolving about a normally stationary axis, the type-wheel shaft mounted in movable supports, mechanism for moving such sup-

ports to effect the bodily movement of the type-wheel in an opposite direction to that in which the surface of the wheel at the printing side thereof is moving, and operative connections interposed between the respective toothed wheels and such mechanism.

56. The combination of a rotating cammed or toothed driver, a toothed wheel normally out of engagement with the driver, a push-rod adapted to impart a partial rotation to the wheel to bring a tooth thereon into position to engage the driver, and means for operating the push-rod, a type-wheel and operative connections between it and the driver.

57. The combination of a rotating cammed or toothed driver, a toothed wheel normally out of engagement with the driver, a push-rod mounted to move endwise and yield laterally and adapted to impart a partial rotation to the wheel to bring a tooth thereon into position to engage the driver, and means for operating the push-rod, a type-wheel and operative connections between it and the driver.

58. The combination of a rotating cammed or toothed driver, a toothed wheel normally out of engagement with the driver, a finger-key, a push-rod operated thereby to impart a partial rotation to the wheel to bring a tooth thereon into position to engage the driver, a type-wheel and operative connections between it and the driver.

59. The combination of the finger-keys, the push-rods in contact therewith, the toothed wheels and the driver, substantially as set forth, a type-wheel and operative connections between it and the driver.

60. The combination of the finger-keys, the push-rods in contact therewith, the toothed wheels, the pawls or latches engaging the wheels, and the driver, substantially as set forth, a type-wheel and operative connections between it and the driver.

61. The combination of the finger-keys, the push-rods in contact therewith, the toothed wheels, the pawls or latches engaging the wheels, the levers operated by the wheels and the driver, substantially as set forth, a type-wheel and operative connections between it and the driver.

62. The combination of the continuously-revolving type-wheel, its shaft, the swinging coincidently-pivoted parts in which the shaft is mounted, means for obstructing the rotation of the type-wheel and thereby causing said parts to swing about their pivots, the parallel shaft 29 and the arms thereon operatively connected with said swinging parts.

63. The combination of the continuously-revolving type-wheel, its shaft, the swinging coincidently-pivoted parts in which the shaft is mounted, means for obstructing the rotation of the type-wheel and thereby causing said parts to swing about their pivots, the parallel shaft 29, the arms thereon operatively connected with said swinging parts, a hammer for taking an impression from the type-wheel and hammer-operating mechan-

ism interposed between the hammer and said parallel shaft and actuated thereby.

64. The combination of the continuously-revolving type-wheel, its shaft, the swinging coincidently-pivoted parts in which the shaft is mounted, means for obstructing the rotation of the type-wheel and thereby causing said parts to swing about their pivots, the parallel shaft 29, the arms thereon operatively connected with said swinging parts, a hammer-actuating arm projecting from said parallel shaft, a hammer and operative connections between said arm and hammer.

65. The combination of a continuously-revolving type-wheel, its shaft, the swinging coincidently-pivoted parts in which the shaft is mounted, means for presenting an obstacle to the rotation of the type-wheel and thereby causing said parts to swing about their axes, the parallel shaft 29 operatively connected with said swinging parts to be rocked thereby, an arm operated by said shaft, a lever operated by the arm and carriage-feed devices operated by the lever.

66. The combination of a continuously-revolving type-wheel, its shaft, the swinging coincidently-pivoted parts in which the shaft is mounted, means for presenting an obstacle to the rotation of the type-wheel and thereby causing said parts to swing about their axes, the parallel shaft 29 operatively connected with said swinging parts to be rocked thereby, an arm operated by the shaft, a lever operated by the arm, carriage-feed devices operated by the lever, a hammer-actuating arm also operated by said shaft, a hammer and operating connections between the arm and hammer.

67. The combination of a continuously-revolving type-wheel, its shaft, the eccentrically-pivoted parts in which the shaft has its bearings, means whereby at will an obstruction may be opposed to the rotation of the type-wheel to cause said parts to swing upon their pivots and thereby maintain the desired character momentarily at the printing-point, a carriage and carriage-feed devices operated by the swing of said parts.

68. The combination of a continuously-revolving type-wheel, its shaft, the eccentrically-pivoted parts in which the shaft has its bearings, means whereby at will an obstruction may be opposed to the rotation of the type-wheel to cause said parts to swing upon their pivots and thereby maintain the desired character momentarily at the printing-point, a carriage, a hammer, and carriage-feed devices and hammer-operating devices actuated by the swinging of said parts.

69. The combination of a type-wheel so mounted and driven as to rotate continuously about its center and be capable of being moved bodily at right angles to its axis of rotation, a wheel having teeth or projections revolving and movable with the type-wheel, a part adapted to be thrown into engagement with said wheel thereby opposing the revolution of

said wheel and the type-wheel about their common center and producing a movement or displacement of the wheel in a plane at right angles to its center of rotation, a series 5 of finger keys or levers, a continuously-revolving driver, a series of devices, one for each lever capable of being actuated by the driver when the corresponding finger-keys are operated and operative connections be- 10 tween each said device and the part adapted to engage the toothed wheel continuously rotating with the type-wheel.

70. The combination of a type-wheel so mounted and driven as to rotate continuously 15 about its center and be capable of being moved bodily at right angles to its axis of rotation, a wheel having teeth or projections revolving and movable with the type-wheel, a part adapted to be thrown into engagement with 20 said wheel thereby opposing the revolution of said wheel and the type-wheel about their common center and producing a movement or displacement of the wheel in a plane at right angles to its center of rotation, a series 25 of finger keys or levers, a continuously-revolving driver, a series of devices, one for each lever capable of being actuated by the driver when the corresponding finger-keys are operated, operative connections between 30 each said device and the part adapted to engage the toothed wheel continuously rotating with the type-wheel and a hammer and operating devices.

71. The combination of a series of finger 35 keys or levers, a continuously-revolving driver, a series of wheels, one for each lever normally at rest but capable of being partially rotated by the driver whenever the corresponding finger-key is depressed, a lever 40 operated by each wheel when so actuated by the driver, a pivoted arm 26, a device for actuating the same operated upon by each wheel-actuated lever, a type-wheel mounted and driven to rotate continuously about its 45 center and capable of movement bodily in a plane at right angles to its axis of rotation, a toothed wheel rotating with the type-wheel and in fixed relation thereto and engaged by said part 26 whenever the same is actuated.

50. 72. The combination of a type-wheel so mounted and driven about a vertical axis as to rotate continuously about its center and be capable of being moved bodily at right angles to its axis of rotation, a wheel having 55 teeth or projections revolving and movable with the type-wheel, a part adapted to be thrown into engagement with said wheel thereby opposing the revolution of said wheel and the type-wheel about their common center and producing a movement or displacement 60 of the wheel in a plane at right angles to its axis of rotation and in the direction described.

73. The combination of a type-wheel so 65 mounted and driven about a vertical axis as to rotate continuously about its center and

be capable of being moved bodily in a direction opposed to the rotary motion of its impression side to maintain any character thereon at rest at the printing-point, a ratchet or toothed wheel of the same diameter as the type-wheel arranged below it and rotating and movable therewith, and an arm or lever adapted at will to engage and obstruct the rotation of said toothed wheel and thereby move the type-wheel bodily as described. 75

74. The combination of a type-wheel so mounted and driven about a vertical axis as to rotate continuously about its center and be capable of being moved bodily in a direction opposed to the rotary motion of its impression side to maintain any character thereon at the printing-point, a ratchet or toothed wheel arranged below the type-wheel and rotating and movable therewith, and an arm or lever adapted at will to engage and obstruct the rotation of said toothed wheel and thereby move the type-wheel bodily as described. 80

75. The combination of a type-wheel so mounted and driven about a vertical axis as to rotate continuously about its center and be capable of being moved bodily in a direction opposed to the rotary motion of its impression side to maintain any character thereon at the printing-point, a ratchet or toothed wheel of the same diameter as the type-wheel arranged below it and rotating and movable therewith, an arm or lever adapted at will to engage and obstruct the rotation of said toothed wheel and thereby move the type-wheel bodily as described. 85

76. The combination of the frame, the type-wheel mounted at one side thereof with its axis vertical, the carriage, an arm located above the carriage and in rear of the type-wheel and extending from one end of the machine toward the type-wheel end, a hammer pivoted upon said arm, a hammer-actuating arm, a latch carried thereby, a lever normally engaged by the latch, operative connections between the hammer and lever, and the inclined or cam projection upon the latch and a fixed surface against which it works whereby when the actuating-arm is moved through a certain distance and the hammer actuated, the latch is disengaged from the hammer-actuating lever. 90

77. The combination of a type-wheel mounted and driven to rotate continuously about its center, a type-wheel shaft, the swinging parts in which it is mounted, means for opposing an obstruction to the rotation of the type-wheel and thereby causing said parts to swing from their normal position thereby maintaining the desired character on the type-wheel at the printing-point, hammer-operating devices actuated by such swinging parts to then take an impression from the type-wheel, means for then disengaging the hammer from its actuating devices whereby its 95 100 105 110 115 120 125 130

stroke is determined and fixed irrespective of the continued movement of said swinging parts.

78. The combination of a continuously-revolving type-wheel, its shaft, the pivoted swinging parts in which the shaft is mounted, means for opposing an obstruction to the rotation of the wheel and thereby causing said parts to swing upon their center, thus maintaining a given character on the wheel at the printing-point, a hammer actuated by said swinging parts during the first portion of their movement to take an impression from the character on the type-wheel and then be disengaged therefrom, a carriage and carriage-feed devices operated by said swinging parts to feed the carriage forward one step during the remaining portion of the movement of said parts.

79. The combination of the driver, the parallel shaft, the short shaft driven thereby, a worm-pinion thereon, a worm-wheel on the driver driven by said pinion, a gear on the short shaft, the type-wheel shaft, a pinion thereon driven by said gear, a type-wheel rotating with the shaft, the pivoted swinging plates in which the type-wheel shaft is mounted, a toothed wheel rotating with the type-wheel, means for engaging the toothed wheel and opposing an obstruction to the rotation of the type-wheel shaft and type-wheel thereby causing the pivoted plates in which the type-wheel shaft is mounted to swing about their pivots, a hammer, means whereby the hammer is actuated to take an impression from the type-wheel during the first portion of the movement of said swinging plates, carriage-actuating devices and means whereby the carriage-actuating devices are operated during the final portion of the movement of said swinging plate to feed the carriage forward one step.

80. The combination of the shaft, a type-wheel mounted to revolve therewith and slide thereon, a key and mechanism interposed between the key and type-wheel whereby when the key is depressed the type-wheel is moved longitudinally upon the shaft, and a roller-stop which limits the movement of the type-wheel and against which the type-wheel revolves when so shifted on its shaft.

81. The combination of the frame, a type-wheel, an inking-roll, a bracket in which the roll is mounted having a squared or angular butt, and a spring bearing upon the butt whereby the roll is normally presented to the type-wheel but may be swung away from it and so be retained by the spring.

82. In a type-writing machine, a carriage, mechanism for automatically returning the carriage to its initial position, the finger-keys, and mechanism for locking the keys during the traverse of the carriage back to its initial position, in combination with a continuously-rotating type-wheel and driver for operating the type-wheel.

83. In a type-writing machine, the combina-

tion of a carriage, mechanism for feeding it forward step by step, a detent-pawl normally engaging its rack, means for returning the carriage to its initial position when the detent-pawl is disengaged therefrom, means for disengaging the detent-pawl from the carriage to permit its automatic return to its initial position, and a locking device for then engaging the levers of the machine to prevent their operation during the return traverse of the carriage to its initial position.

84. In a type-writing machine, the combination of a continuously-revolving driver, a continuously-revolving type-wheel, so mounted as to be moved bodily in a direction opposed to that in which the surface from which an impression is to be taken is traveling, a hammer for taking impressions from the type-wheel, a carriage, mechanism for each finger-key actuated by the driver when its finger-key is depressed to move the type-wheel bodily as stated, means for operating the hammer during the early portion of said movement of the type-wheel and means for feeding the carriage during the latter portion of such movement of the type-wheel and after the hammer has been actuated to take an impression therefrom.

85. The combination of a continuously-revolving driver, a series of finger-keys, a continuously-revolving type-wheel having its shaft mounted in parts adapted to swing upon their center of motion to move the type-wheel bodily in a direction opposed to that of its surface from which an impression is to be taken, means operated by the continuously-revolving driver to, upon the depression of the finger-key, oppose an obstruction to the rotation of the type-wheel about its axis and thereby cause the parts upon which it is mounted to swing as stated, a hammer operated by the continuously-revolving driver to take an impression from the wheel when so moved bodily, a lever also operated by the power from the continuously-revolving driver, a carriage adapted to be fed forward step by step, and mechanism actuated by said lever to feed the carriage forward after the hammer has been operated to take an impression.

86. In a type-writing machine, the combination of a carriage, mechanism for feeding it forward step by step, a spring-drum tending constantly to return it to its normal position, a detent-pawl normally engaging the rack of the carriage, a pivoted lever normally engaging the detent-pawl to hold it in engagement with the rack, but adapted when moved to operate the pawl to throw it out of engagement with the rack, a latch having two arms, one engaging said lever and the other occupying a position to be struck by the pin or projection on the carriage, whereby when the carriage approaches its extreme forward position, the latch is operated to disengage the detent-pawl from the rack.

87. In a type-writing machine the combination of the carriage adapted to be fed forward step by step, mechanism for so feeding it operated by the depression of the finger-keys, a 5 detent-pawl normally engaging the rack of the carriage, a lever having a projection normally holding the detent-pawl in engagement with the rack but capable upon the movement of the lever of disengaging the pawl from the 10 rack, the three-armed latch, one arm of which holds the lever in normal relation to the detent-pawl, another arm of which occupies a position to be struck by a pin on the carriage when the carriage approaches its extreme forward position and thereby disengage the latch 15 from the lever and cause the disengagement of the detent-pawl from the rack, a finger-key and operative connections interposed between the key and the third arm of the three-armed 20 latch to, upon the depression of said key, operate the latch to release the rack from the detent-pawl.

88. The combination of a carriage adapted to be fed forward step by step, the carriage-feed-operating lever 87, the pivoted lever 89, the carriage-actuating pawl carried thereby and having a cam projection thereon, a projection on the carriage that normally holds the pawl out of engagement with the rack of the 25 carriage, the detent-pawl normally engaging the rack, the lever 104, the projection thereon serving to hold the detent-pawl normally in engagement with the rack, a projection on said pawl against which the projection on the 30 lever 104 works to disengage the detent-pawl from the rack, a latch for holding the projection on the lever 104 normally in engagement with the detent-pawl, and means for tripping the latch to disengage the detent-pawl from 35 the rack and permit the return of the carriage to its initial position.

89. The combination of the carriage, the paper-feed roll mounted to turn therein, a shaft capable of turning independently within the 40 feed-roll, a cam mounted upon the frame, a projection on the shaft adapted to engage the cam as the carriage returns to its initial position, and connections between the shaft and roll that cause the rotation of the roll a given 45 distance in one direction when the projection on the shaft rides along the surface of the cam.

90. The combination of the carriage, a feed-roll turning in bearings thereon, a shaft extending through the roll, a latch-and-pawl connection between the roll and the shaft at one end, a spring connection between the shaft and the roll at the opposite end, a projection fast on the shaft and a cam on the 50 frame against which such projection works as the carriage returns to its initial position,

whereby the roll is partially rotated to space the lines on the paper carried by it.

91. The combination of the carriage, a feed-roll turning in bearings thereon, a shaft extending through the roll, a latch-and-pawl connection between the roll and the shaft at one end, a spring connection between the shaft and the roll at the opposite end, a projection fast on the shaft, a cam on the frame 65 against which such projection works as the carriage returns to its initial position, whereby the roll is partially rotated to space the lines on the paper carried by it, and means for setting the cam in different positions to 70 vary the spacing.

92. The combination of a carriage, a paper-feed roll mounted to turn thereon, a shaft turning within the roll, a yielding connection between the shaft and the roll at one end, a projection upon the shaft, a cam on the frame 75 against which it works as the carriage returns to its initial position, a toothed wheel on the opposite end of the roll, and a pawl on the shaft engaging the wheel.

85 93. The combination of a carriage, a paper-feed roll mounted to turn thereon, a shaft turning within the roll, a yielding connection between the shaft and the roll at one end, a projection upon the shaft, a cam on the frame 90 against which it works as the carriage returns to its initial position, a toothed wheel on the opposite end of the roll, a pawl on the shaft engaging the wheel, and means for setting the pawl either in or out of engagement 95 with the wheel.

94. The combination of a continuously-revolving type-wheel, movable bearings in which it is mounted, mechanism for moving said bearings normally disconnected therefrom, a driver and a series of devices each actuated at will by the driver to operate said mechanism and thereby move said bearings to maintain a given character on the type-wheel at rest at the printing-point.

105 95. The combination of a continuously-revolving type-wheel, movable bearings in which it is mounted, mechanism for moving said bearings normally disconnected therefrom, a driver, a series of devices each actuated at will by the driver to operate said mechanism and thereby move said bearings to maintain a given character on the type-wheel at rest at the printing-point, and means for then taking an impression from such 110 character.

In testimony whereof I have hereunto subscribed my name.

OLUF TYBERG.
